UNITED STATES PATENT OFFICE.

CHARLES NELSON, OF EAST NEW YORK, N. Y.

MACHINE FOR FORMING MUFFLING-STRIPS FOR SLATE-FRAMES.

SPECIFICATION forming part of Letters Patent No. 281,787, dated July 24, 1883.

Application filed March 31, 1883. (No model.)

To all whom it may concern:

Be it known that I, CHARLES NELSON, of East New York, in the county of Kings and State of New York, have invented certain new 5 and useful Improvements in Guides for Making Spirally-Corded Muffling-Strips for Slate-Frames, of which the following is a specification.

This invention has reference to an improved 10 guide device for making spirally-corded noise-muffling strips for slate-frames in a cheap, quick, and uniform manner without the employment of specially-skilled hands; and the invention consists of a guide composed of a 15 base part having parallel guide-pieces that are inclined at a suitable angle to the longitudinal axis of the base, and of somewhat greater width at the top than at the base. The upper edges of the guide-pieces are centrally recessed, 20 equal to the width of the muffling-strip, which is placed into the recesses and then covered with fabric and a spirally-wound retaining-cord.

In the accompanying drawings, Figure 1 25 represents a side elevation, Fig. 2 a plan, and Fig. 3 a vertical transverse section on line yy , Fig. 2, of my improved guide for making spirally-corded muffling-strips for slate-frames.

Similar letters of reference indicate corresponding parts.

In the drawings, A represents the base of my improved guide for making spirally-corded noise-muffling strips for slate-frames, which base is made of T-shaped cross-section, and 35 secured to wooden supporting side pieces of suitable thickness. The base A is provided with a number of upright parallel guide-pieces, B, that are arranged at a suitable angle of inclination to the longitudinal axis of the guide, 40 according to the pitch that is to be given to the cord to be wound spirally around the muffling-strip. Between the guide-pieces B B intermediate recesses, $b b$, are formed, which are wider at the base than at the top, as the guide-pieces B are made wider at the top than at the 45 bottom. The upper surface of the guide-pieces B B is centrally grooved in the direc-

tion of the longitudinal axis of the guide, the grooves $b' b'$ being equal in width and depth to the strip d to be corded.

In making the noise-muffling strip a flannel covering, e, is first placed into the groove, and then the wooden strip d pressed down on the flannel into the groove. A cord, f, is then passed through the first recess b , at one end of 50 the guide at the lower wider part of the recess, then drawn taut diagonally across the top of the strip and around the edge of the same, then in the next recess b , below the strip, to the other side, then again diagonally over the 55 strip, and so on through all the recesses, whereby the flannel covering is tightly applied to the strip and the cord wound in spiral and equidistant convolutions around the same. The spirally-corded strip is finally removed 60 from the guide and applied around the edge of a slate-frame, so as to muffle the noise in handling the slate and protect the same against 65 injury.

Having thus described my invention, I claim 70 as new and desire to secure by Letters Patent—

1. A guide for making spirally-corded noise-muffling strips for slate-frames, consisting of a base, A, and of laterally-inclined guide-pieces B B, which are separated by intermediate recesses, $b b$, and provided with top recesses for the strip to be wound, substantially 75 as set forth.

2. A guide for making spirally-corded noise-muffling strips for slate-frames, consisting of 80 a base, A, laterally-inclined guide-pieces B B, and intermediate recesses, $b b$, the guide-pieces B being narrower at the base than at the top, and provided with central top recesses, $b' b'$, in line with the longitudinal axis of the guide 85 device, substantially as and for the purpose set forth.

In testimony that I claim the foregoing as my invention I have signed my name in presence of two subscribing witnesses.

CHARLES NELSON.
